INVENTOR:

Richard Jacks

David C. Brown Attorney,

UNITED STATES PATENT OFFICE.

RICHARD JACKS, OF MEADOW VALLEY, CALIFORNIA.

WAGON-REACH COUPLING.

SPECIFICATION forming part of Letters Patent No. 288,707, dated November 20, 1883.

Application filed August 18, 1883. (No model.)

To all whom it may concern:

Be it known that I, RICHARD JACKS, a citizen of the United States, residing in Meadow Valley, county of Plumas, State of California, have made and invented certain new and useful Improvements in Wagon-Reach Couplings, of which the following is a full, clear, and exact specification, the accompanying drawings forming a part thereof.

10 My invention relates to a novel coupling for connecting reach to axle in running-gear of wagons. The coupling partakes of the character of a universal joint. It is constructed and provided for the purpose of permitting free swing and independent movement within limits of the reach and axle, while at the same time it affords a strong and effective fastening for these parts together.

15 The manner in which I proceed to produce, construct, and apply my said invention is as follows, in the drawings referred to Figure 1 being a perspective view of the front axle, bolster, and reach; Fig. 2, a top view of same; Fig. 3, a longitudinal section in elevation.

20 A represents the front axle of a wagon, and B is the reach connecting the front and rear axles.

The hounds are seen at c c, and the sway-bar at d.

25 E is a stirrup-plate bent into semicircular form, and having two screw-threaded ends, e e, that are straight bolt-like continuations of the circular part. They are also of equal length, and extend backward from the broad stirrup E parallel with each other. The plate E is secured to the back of the axle, at the point where the reach is to be attached, by passing the ends e e through holes in the axle, or through apertures between the axle and the 30 bolster-bar f, that is clipped to the axle. A strong and secure fastening is insured by using plates g g upon the front and rear, and then screwing down nuts h, and, if necessary, using jam-nuts. This mode of fastening is seen in 35 Figs. 1 and 2 of the drawings.

40 Over the end of the reach B is secured a strap-iron, H, having an eye, h', for a coupling-bolt, I, to pass through. The bend or loop of the stirrup E is slotted also for the passage of 45 this bolt the slot being wide enough for free play of the bolt, and extending from side to

side to give sufficient lateral movement as well. The head of the coupling-bolt is curved on the back face, so as to fit the curved bend or loop of the stirrup. This head consists of a convex 55 saddle-block, J, with a square hole in the center, through which the shank of the bolt having corresponding form is inserted. In the rounded face are recesses j, to receive friction-rollers k k, that are placed in line, one above 60 and the other below the bolt-shank. These rollers are employed to take the friction from the saddle-block. The bolt and saddle-block can be one structure; or they can be detached or separable parts, as I have represented in the 65 drawings. In such construction the shank of the bolt will be headed on the outside, and the face of the block that it bears against will be flat.

The two parts E H are secured to the end of 70 the reach and to the middle of the axle, respectively, the saddle-block being slipped into place, with the coupling-bolt extending through the slot, before the part E is secured to the axle. The parts of the coupling are then united by 75 passing the end of the coupling-bolt through the eye in the part H, and screwing down a nut, l, placed on the threaded end of the bolt. The strap H is fixed to the reach to give sufficient room between the head of the strap and 80 the end of the reach for placing and removing this holding-nut.

A rubber spring or thick elastic washer, m, is interposed between the parts of the coupling, and when they are drawn together by the coupling-bolt and nut a strong and firm connection is produced, the spring yielding to give the saddle-block and stirrup movement upon each other as the axle swings, and at the same time taking up and preventing any loose play. 85

90 By connecting reach and axle by a flexible or jointed coupling in this manner, the rack and strain upon the running-gear of wagons will be greatly reduced, and their durability and greater comfort and ease in riding as well 95 are increased to a high degree beyond that which is attained in and by rigid connection of these parts.

Having thus fully described my invention, what I claim, and desire to secure by Letters Patent, is—

1. A jointed or flexible reach-coupling for

running-gear of wagons, consisting of the parts E H, adapted to be fixed to the end of a reach and the middle of the axle, respectively, the coupling-bolt I, saddle-block J, and spring m.

5 2. The combination of the stirrup-plate E, having the slot for the play of the bolt, the saddle-block J, the strap H, and the coupling-bolt I.

3. The combination, with the stirrup-plate

E, having means for fastening it to the axle, 10 of the saddle-block J, with friction-rollers, and the coupling-bolt I, for making attachment of said saddle-block with the end of the reach.

RICHARD JACKS. [L. S.]
